UNITED STATES PATENT OFFICE.

HEINRICH SCHÜNEMANN, OF SPANDAU, GERMANY, ASSIGNOR TO MESSRS. NEUBURG'SCHE VERWALTUNGSGESELLSCHAFT M. B. H., GEREONSHAUS, OF COLOGNE, GERMANY, A CORPORATION OF GERMANY.

APPARATUS FOR UNIFORMLY FEEDING CUT TOBACCO TO THE ROD-FORMING MECHANISM OF CIGARETTE-MAKING MACHINES.

Application filed November 23, 1927, Serial No. 235,315, and in Germany April 23, 1927.

The means hitherto employed for feeding the cut tobacco to the rod forming tape of cigarette machines have presented the disadvantage that the feed is not uniform, but 5 is subject to considerable fluctuations, as is evidenced by a considerable difference in the weight of the finished cigarettes.

The present invention has for its object a process by means of which it is possible 10 to overcome this disadvantage.

The essence of the present process is comprised in the circumstance that the cut tobacco which has previously been loosened as much as possible in a suitable device is fed 15 first of all into a slide that oscillates vertically. The cut tobacco at the end of this slide, in which it lies in a fairly large layer, owing to the oscillating motion is received by a pin roller to which the same oscillating 20 motion is imparted and which constricts the exit of the slide, so that this pin roller is always charged with a uniformly thick layer of cut tobacco, even when there are certain differences in the uniformity of the 25 feed of the tobacco to the slide. From this pin roller and by means of a pin roller of larger diameter, which rotates at a greater speed but does not oscillate, a uniformly thin layer is drawn and then fed by suitable 30 means to the rod forming belt.

A sectional elevation of a form of apparatus for carrying out the present process is shown in the accompanying drawings.

The thoroughly loosened tobacco is first 35 of all transferred to a vertical slide 1. The cross section of this slide 1 is a flat rectangle. The slide is movably suspended on parallel flat springs 2. The lower outlet of the slide is closed by means of a pin roller 6. A vertical oscillating movement is imparted to 40 the slide and to the pin roller. For this purpose an eccentric 7 is provided, which by means of a connecting rod 8, and a cross head 9, imparts reciprocating motion to a 45 connecting rod 10.

This connecting rod slides in a guide 13 attached to the slide 1. Tensioned springs 11 and 12 are arranged on both sides of the guide 13 between collars 14 adjustable on the 50 connecting rod 10'. The tension of the springs can be varied by means of the collars 14. In addition to this the container 1 is fitted with a leather lined distance piece

3 which is arranged opposite to a counter distance piece 4 that can be adjusted by 55 means of a screwed spindle 5. The slide 1 which is operated by the eccentric 7 by means of the springs 11, 12, receives through the counter distance piece 4 and in accordance with its adjustment, an earlier or later limit 60 of lift movement, so that a harder or softer impact of the slide ensues. The pin roller 6 is revolvably supported in the side cheeks of the slide 1, and is simultaneously rotated so that it not only has an oscillating 65 motion but also rotates and thereby draws the tobacco deposited owing to the oscillating motion in a fairly thick layer in the outlet of the slide 1 in a layer the thickness of which corresponds to the length of a peg. 70 This compact layer is then received by a rotating but non-oscillatory pin roller having a greater peripheral speed, or if of the same diameter rotating at the same speed as roller 6. This latter pin roller is indicated 75 by 15 in the drawing, the layer of tobacco being held fast between the pins by means of wire springs such as 19.

The reduction of the density of the layer 80 of tobacco passing from roller 6 to roller 15 is of special importance for securing a uniform spreading of the tobacco. In accordance with this reduced thickness of the layer the pins of the roller 15 should be dimensioned in proportion to the roller 6. 85 The tobacco is transferred from the roller 15 by means of a drum 16 on to the conveyor belt 17 and into the rod forming channel 18.

It must be pointed out that endless pin 90 belts can also be used in the place of the rotating pin rollers for drawing the tobacco from the oscillating slide, and that likewise by connecting up several pin rollers of different peripheral speed one behind the 95 other, a further reduction in the thickness of the layer of tobacco supplied by the pin roller 6 to the rod belt can be effected.

Claims:

1. Apparatus for uniformly feeding cut 100 tobacco to the rod forming belt or cigarette machines, comprising a substantially perpendicular hollow chute open at the opposite ends thereof, means for feeding the cut tobacco to the upper end of the chute, means 105 for imparting reciprocating movement to

said chute in the direction of its length, a rotating pin roller mounted on said chute and closing the lower open end thereof adapted to move up and down with said chute and to remove the tobacco from the lower end of said chute and to convey it therefrom.

2. Apparatus for uniformly feeding cut tobacco to the rod forming belt of cigarette

machines as claimed in claim 3 and in combination therewith of a rotating pin roller receiving the tobacco from said first mentioned roller, said second pin roller having a greater peripheral speed than said first roller and said second pin roller delivering 15 said tobacco to the rod forming belt.

HEINRICH SCHÜNEMANN.
